UNITED STATES PATENT OFFICE.

CARL A. ANDERSON, OF LOWELL, MASSACHUSETTS, ASSIGNOR TO REECE BUTTON HOLE MACHINE COMPANY, OF BOSTON, MASSACHUSETTS, A CORPORATION OF MAINE.

BUTTON-SEWING MACHINE.

1,083,907.

Specification of Letters Patent.

Patented Jan. 13, 1914.

Application filed March 8, 1913. Serial No. 752,963.

To all whom it may concern:

Be it known that I, CARL A. ANDERSON, a subject of the King of Sweden, residing at Lowell, in the county of Middlesex and State 5 of Massachusetts, have invented certain new and useful Improvements in Button-Sewing Machines, of which the following is a specification.

This invention relates to machines for 10 sewing buttons to shoes, or other material or articles of manufacture, and has particular reference to that type of machine adapted to fasten shank-eye buttons by means of a single thread, employing primary and secondary loops, one of which passes through the shank-eye of the button, the other or secondary loop being passed through the primary loop and then cast over the button and interlocked with the primary loop below 20 the button.

One object of my invention is to provide a machine employing two needles operating from opposite sides of the work-table and performing their complete operations for 25 attaching the button while the button and the work to which it is attached is held stationary.

In another aspect an object of my apparatus is to firmly lock each of a series of 30 shank-eye buttons by two loops of a single thread, each carried from the under or rear or thread side of the work to the upper or front or button side, by means of two independent needles, the first constructed of 35 hooked form to enable it to disengage the thread after drawing it through the work, the second needle fitted at the under side to so coöperate with the first that the two thread loops can be mutually engaged above 40 the work, interlocked with the button eye and tightened.

Other objects and advantages will appear hereinafter or will be obvious to those skilled in the art.

To this end my invention consists of the improvements which I shall now proceed to describe and claim.

Of the accompanying drawings:—Figure 1 is a side elevation of so much of a sewing-machine as is necessary to illustrate my invention. Fig. 2 is an elevation from the right of Fig. 1. Figs. 3 to 7, inclusive, are detail figures, illustrating the operation of the machine.

Similar reference characters indicate similar parts in all of the views. 55

It may be mentioned at the outset that I do not attempt to illustrate parts of the machine, such as the work feed and take-up devices, as the same may be of any preferred 60 or well known construction.

The base of the machine is indicated at 10, the arm 11 rising from said base and having a head 12 for the bars of the needle, presser-foot and loop-spreader. The main 65 shaft 13 is provided with a cam 14 for operating the rod or link 15 which is connected at its upper end to a lever 16 pivoted at 17 in the arm of the machine. The particular shape of the cam 14 is not illustrated, as 70 the same forms no necessary part of my present invention. It is, of course, so formed as to impart to the needle the customary movements to cause the needle to penetrate the work and have the usual slight dwell to 75 release the loop of thread, as hereinafter described. The needle-bar 18 having a needle 19 provided with an open eye or hook, is mounted in suitable ways in the head 12. A foot 20, to bear on the work has its shank 21 secured to the head 12, as by screws 22. Since 80 the buttons are supplied above the foot 20, said foot is, as nearly all presser-feet are, slotted in the direction of movement of the work as the latter is fed by suitable mechanism not shown. 85

The needle-bar 18 is provided with a pin 23 which extends into a slot formed in the head 12, or a suitable piece carried by said head, said slot having an inclined portion 90 24, and a straight portion 25, so that the first downward movement of the needle-bar will result in its having a rotary movement imparted thereto, the latter part of the downward movement, as the pin 23 rides 95 along the straight portion 25 of the slot, being in a direct line, without rotation. The inclined portion 24 of the slot imparts substantially a quarter turn to the needle.

In order that the lever 16 may cause the 100 needle-bar to have the reciprocating and turning movements just mentioned, the needle-bar has secured thereto collars 26 between which is a sleeve 27, said sleeve surrounding the needle-bar and having pins 28 105 entering elongated openings in the yoke-shaped end 29 of the lever 16.

A cam 30 carried by the main shaft 13

actuates a rod or link 31, the upper end of which is connected to an arm 32 at one end of a rock-shaft 33 mounted in bearings 34 in the arm 11 of the machine. An arm 35 at the other end of the rock-shaft is formed with a slot engaging a pin 36 projecting from the bar 37 of the loop-spreader 38. The loop-spreader 38 has a tapered and inclined upper surface and a hollow lower surface, for reasons hereinafter explained. The mounting of the loop-spreader-bar so as to cause it to have a swinging movement, will be hereinafter explained.

The front end of the main shaft 13 carries a disk 39 provided with a cam groove, different portions of which are indicated at 40, 41, 42 and 43. A roll 44 carried by a lever 45 pivoted at 46 engages said cam groove. The other end 47 of lever 45 is yoke-shaped and provided with elongated openings engaging pins 48 carried by a sleeve 49 between collars 50 secured to a bar 51 mounted to slide in an inclined direction in bearings 52, 53. The bearing 53 is formed with a slot or groove, which is straight for the greater portion of its length, as at 55, and is inclined at one end, as at 54, a pin 56 projecting from the bar 51 entering said slot so that as the bar 51 is reciprocated by means of the lever 45, it will be guided without rotation or turning movement during the greater portion of the reciprocating movement, but will be swung or turned about a portion of a revolution as the pin 56 moves along the inclined portion 54 of the groove in said bearing 53.

The upper end of the bar 51 is offset, as at 57, and carries a needle 58, the eye of which is closed, as best shown in Figs. 3 to 6. As will be hereinafter explained, the lower needle 58 is given a lateral swinging movement, owing to the fact that it is carried by an offset portion 57 of the bar 51, and due to the partial rotation of the bar 51 when its pin 56 is moving along the inclined portion 54 of the guide groove.

A suitable work-table is indicated at 59, said table being carried by a bar 60 slidiably mounted in ways 61 and held yieldingly in its upper position by a suitable spring 62. The work-table 59 is preferably provided with a spring clip 63 with which the thread *a* may be engaged when starting the sewing operation, as hereinafter described.

The loop-spreader bar 37 is mounted in a slide bearing 64 which is pivotally supported at 65 so that said bar 37 may swing. The bar 37 is provided with a pin 66 which enters a guide groove 67, 68, formed in a stationary part of the head 12, so that when the spreader 38 is actuated by the rock-shaft, its first downward movement will be an inclined direction, due to the pin 66 riding along the portion 67 of the guide groove, the last portion of the downward movement

of the loop spreader being substantially vertical, due to the pin 66 riding along the portion 68 of the guide groove. In operation the buttons are placed successively and one at a time, substantially in the position shown in Fig. 3, and this may be done by hand, although in practice a suitable magazine and chute and escapement mechanism will preferably be provided for supplying the buttons to the position mentioned. When the first button is to be applied, the end of the thread *a* may be temporarily caught and held by the spring clip 63. The timing of the operations of the different parts of the machine is such that the upper needle 19 passes down through the shank-eye of the button, as shown in Fig. 3, the lower needle 58 being at this time in position so that the thread leading from the clip 63 to the closed eye of the lower needle is behind the upper needle, but close to it. At this time the pin 56 of the lower needle bar 51 is at the lower end of the portion 55 of the guide slot. Then the cam disk 39, revolving in the direction of the arrow (Fig. 2) causes the portion 41 of the cam groove to act upon lever 45 to give the latter a slight oscillation so that the said pin 56 moves down the inclined portion 54 of the guide slot, and back again, so that the needle-bar 51 is given a sufficient quick turning movement to swing the lower needle 58, owing to the offset portion 57 of the bar 51, to carry the thread *a* into the hook of the upper needle 19. Then the portion 40 of the cam groove of disk 39 holds the lever 45 in position so that lower needle 58 remains in the position shown in Fig. 3, but with the thread having been thrown into the hook of the upper needle 19, which latter, as it rises, draws a primary loop of the thread 105 up through the button-eye, as shown in Fig. 4. The upper needle 19 turns from its axial position shown in Fig. 3, to that shown in Fig. 4, due to the pin 23, of the needle-bar 18 passing from the straight slot or groove 23 into and along the inclined slot or groove 24, and just before the operation shown in Fig. 3 takes place, the needle 19 is given a slight downward movement and dwell, as is well known in many sewing-machines, to 110 open the primary loop to release it from the hook of the upper needle. Just before the primary loop is entirely released from the upper needle, the lower needle is actuated to the position shown in Fig. 5, so as to carry 120 a secondary loop of the thread up through the primary loop. This last-mentioned motion of the needle 58 is caused by the action of the portion 43 of the cam groove and disk 39 upon the lever 45, as best shown in Fig. 125 2. Owing to the position and the inclination of the lower needle and its bar, the secondary loop is carried up past the eye of the button, the button not having been moved in the meantime. Fig. 5, to be exact,

130

illustrates a position of the parts after the needle 58 has commenced to retreat so that the secondary loop is opened above the point where it passes through the primary loop.

5 The mounting and operation of the loop-spreader 38 is such that it moves from the position shown in Fig. 2 in a downwardly inclined direction, being guided by the pin 66 riding along the portion 67 of the guide-groove in the head 12, the tapering point of the loop-spreader entering the secondary loop, as shown in Fig. 5, and then continuing down to the position shown in Fig. 6. The last portion of the downward movement 10 of the loop-spreader is substantially vertical, being effected by the portion 68 of the guide groove acting on the pin 66 of the loop-spreader shank, the recessed lower surface of the loop-spreader covering, or 15 partially covering the button so as to guide the secondary loop over the button as the take-up (not shown) acts to tighten the stitch. In practice the relative operations of the take-up and the loop-spreader are 20 such that the loop-spreader permits the take-up to act so as to slide the secondary loop off from the said loop-spreader.

In Fig. 7 I illustrate the interlocking of the primary and secondary loops under the 25 action of the take-up and after the loop-spreader has left the secondary loop, it being understood, of course, that the take-up will act later to tighten the stitch still further than indicated in Fig. 7.

30 After the completion of the attaching of one button as explained, the feed mechanism (not shown) will advance the work to a position for the attachment of the next button, the upper needle 19 next moving 40 from the position shown in Fig. 2, to that shown in Fig. 3, preparatory to forming the next primary loop.

The reason for the rotation or turning of the upper needle-bar is to enable the said upper needle, which is a hooked eye needle, to have the thread thrown into said hook by the lower needle as described, and to then turn to position so that said primary loop will be presented properly to enable 50 the lower needle to insert the secondary loop through it.

I claim:

1. A button-sewing machine having a work-support, and stitch-forming mechanism whereby interlocking primary and secondary loops are formed on the same side of the fabric as the button-eye and engaged with said eye, said mechanism including two needles movable alternately in paths 55 traversing the work-support at two separate points.

2. A button-sewing machine having a work-support, and stitch-forming mechanism whereby interlocking primary and secondary loops are formed on the same side

of the fabric as the button-eye and engaged with said eye, said mechanism including two needles, movable in intersecting paths, and means for reciprocating the needles alternately. 70

3. A button-sewing machine having a work-support, and stitch-forming mechanism including upper and lower needles, means for reciprocating the upper needle and turning it relatively to its longitudinal center, and means for reciprocating the lower needle in a path at an angle to the upper needle and swinging it laterally. 75

4. A button-sewing machine having a work-support, and stitch-forming mechanism whereby interlocking primary and secondary loops are formed on the same side of the fabric as the button-eye and engaged with said eye, said mechanism including upper and lower needles movable in relatively inclined paths, one needle having a closed eye and the other a hook or open eye, and means for reciprocating the needles alternately. 80

5. A button-sewing machine having a work-support, and stitch-forming mechanism including an upper needle and a lower needle, one of which is movable in a path through the button-eye and the other at one side of the said eye, means being provided 90 whereby loops formed by the two needles are interlocked on the same side of the fabric as the button. 95

6. A button-sewing machine having a work-support, stitch-forming mechanism including two needles, one of which is movable in a path through the button-eye, and the other at one side of the said eye, means being provided whereby loops formed by the two needles are interlocked, and a loop-spreader to engage the loop formed by one needle and cast it over the button. 100

7. A button-sewing machine having a work-support, and stitch-forming mechanism including two needles, one of which is movable in a path through the button-eye, and the other at one side of the said eye, means being provided whereby loops formed by the two needles are interlocked, a loop-spreader to engage the loop formed by one 110 needle, and cast it over the button, said spreader having an inclined tapering upper surface and a recessed lower surface, means being provided for imparting to said spreader a motion in a downwardly inclined 115 direction.

8. A button-sewing machine having a work-support, a stitch-forming mechanism including an upper needle having a hooked eye, and a lower needle having a closed eye, 120 said needles being movable in relatively inclined paths, means for reciprocating said needles alternately, and means for shifting the lower needle laterally to cause it to lay the thread in the hook of the upper needle. 125

9. A button-sewing machine having a work-support, a stitch-forming mechanism including an upper needle having a hooked eye, and a lower needle having a closed eye, 5 said needles being movable in relatively inclined paths, means for reciprocating said needles alternately, means for shifting the lower needle laterally to cause it to lay the thread in the hook of the upper needle, a 10 loop-spreader, and means for moving said spreader in a downwardly inclined direction to enter a loop formed by the lower needle.
10. Apparatus for attaching shank-eye 15 buttons by a single thread, including in combination, a device for holding a piece of work, to the front side of which the buttons are to be attached by a single thread supplied at the rear side, a needle constructed and fitted for taking the thread 20 at the rear side of the work and carrying a loop thereof through the work, and for thereafter disengaging the thread, and a second needle fitted at the rear side of the 25 work for carrying a second loop of the thread through the work, and engaging it at the front side of the work with the loop formed by the first needle, said two needles having different paths of movement so related that the second needle in advancing to 30 form the second loop enters point-first in the first loop while the first loop is held by the first needle, whereby such loops may be interlocked with the button-eye and the 35 loops tightened to firmly secure the button to the work.
11. Apparatus for attaching shank-eye 40 buttons by a single thread, including in combination, a device for holding a piece of work, to the front side of which the buttons are to be attached by a single thread supplied at the rear side, a needle constructed and fitted for taking the thread at 45 the rear side of the work and carrying a loop thereof through the work, and for thereafter entirely disengaging the thread
- before each button is fully attached, and a second needle fitted at the rear side of the work for carrying a second loop of the thread through the work, and engaging it 50 at the front side of the work with the loop formed by the first needle, whereby such loops may be interlocked with the button eye and the loops tightened to firmly secure the button to the work, said second needle 55 being an eye-needle constructed to maintain permanent engagement with the thread throughout the attachment of a series of buttons.
12. Apparatus for attaching shank-eye 60 buttons by a single thread, including in combination, a device for holding a piece of work, to the front side of which the buttons are to be attached by a single thread supplied at the rear side, a needle constructed 65 and fitted for taking the thread at the rear side of the work and carrying a loop thereof first through the work and then through the eye of a button, and for thereafter disengaging the thread, and a second needle fitted 70 at the rear side of the work for carrying a second loop of the thread through the work, and engaging it at the front side of the work with the loop formed by the first needle, said second needle being an eye- 75 needle constructed to maintain constant engagement with the thread throughout the attachment of a series of buttons, and to so move at the rear of the work as to give thread to the first needle at the rear of the 80 work, and a spreader constructed and fitted for taking part in casting such second loop over the button head, whereby the loops may be tightened and the button thereby firmly secured to the work. 85

In testimony whereof I have affixed my signature, in presence of two witnesses.
